DESIGN FOR A RADIO RECEIVING CABINET

Frederick M. Breen, New York, N. Y., assignor to
Dictograph Products Company, Inc., a corpo-
ration of Delaware

Application October 19, 1936, Serial No. 65,359

Term of patent 3½ years

To all whom it may concern:

Be it known that I, Frederick M. Breen, a citizen of the United States and resident of the city, county, and State of New York, have invented a new, original, and ornamental Design for a Radio Receiving Cabinet, of which the following is a specification, reference being had to the accompanying drawing, forming part thereof.

Figure 1 is a front perspective view of a radio receiving cabinet embodying my novel design.

Figure 2 is a rear perspective view of a radio receiving cabinet shown in Figure 1.

Figure 3 is a front perspective view of the radio receiving cabinet shown in Figure 1, and with the sliding front cover in closed position.

I claim:

The ornamental design for a radio receiving cabinet substantially as shown.

FREDERICK M. BREEN.
